MILKING STOOL

Park Lester Newbold, Cedar Rapids, Iowa

Application April 19, 1937, Serial No. 137,627

5 Claims. (Cl. 31—57)

This invention relates to milking stools and has particular relation to a combination stool and pail holder for use in milking.

One of the difficulties in milking cows is to hold the pail in proper tilted position so that the milking operation can be accomplished to the greatest efficiency and to prevent the pail from being upset.

It is an object of my invention to provide a new and improved milking stool of simple and inexpensive construction which is not readily upset.

Another object of my invention is to provide means for holding the bucket in tipped or tilted position in such manner that it cannot be readily upset and to provide means for protecting the bucket from upsetting.

Another object of my invention is to provide a holding means for a milking bucket which will either hold it in tilted position or support it in normal position so that the bottom of the pail does not rest upon the ground.

Another object of my invention is to provide pail holding means which may be readily adjusted for different sizes of pails.

Other and further features and objects of the invention will be more apparent to those skilled in the art upon a consideration of the accompanying drawing and following specifications, wherein is disclosed a single exemplary embodiment of the invention, with the understanding, however, that such changes may be made therein as fall within the scope of the appended claims, without departing from the spirit of the invention.

Figure 1 is a view in perspective of a stool constructed according to one embodiment of my invention, and

Figure 2 is a view in perspective taken from another viewpoint and illustrating particularly the pail supporting means and means for adjusting the pail support to support different sizes of pails.

Referring now to the drawing a preferred embodiment of my invention includes a stool indicated generally at 10 and a pail supporting and protecting structure indicated generally at 11. I preferably join these two elements so that the weight of the operator holds the pail support steady, and the stool and pail support structure is so disposed that the weight of the operator and the position of the stool provide a lever arm to press the pail support firmly against the ground.

Furthermore, the position of the stool and the

pail support are such that the inner edge of the stool is substantially at the center of balance of the structure so that it is readily carried about by the operator.

The stool-support structure consists of uprights 12 and 13, cross braces 14 and 16, and top and bottom braces 17 and 18. These members may be bolted together or nailed together as desired. This main support structure supports what may be termed the outer portion of the seat 19, and the inner end of the seat is supported by braces 21 and 22 joined at their upper ends by means of a cross brace 23.

I then provide pail support frame members 24 and 26 secured at their outer ends to the inner sides of support members 12 and 13. The inner ends of the members 24 and 26 are joined by a pail support board or platform 27 which acts as a support for the pail when it is in the vertical position shown in dotted lines in Figure 2. A pair of pail support arms 28 and 29 are provided and these are secured to the inner ends of members 24 and 26 and slant upwardly to a position within the upper ends of the members 12 and 13 where they are secured by means of bolts or the like indicated at 31. The inner ends of the members 24, 26, 28 and 29 are covered by means of braces 32 and 33. The top cover brace member is cut away in the arc of a circle as indicated at 34 to receive the pail. The ends of members 27, 32 and 33 are covered by means of plates 36. The members 28 and 29 are convergent at their upper ends so that these members form a wedge for holding the pail 37 in the tilted position shown in Figure 1 with the lower edge of the pail resting on the platform 27 while in this tilted position.

Another complementary cross-member 38 is provided which is also cut away in the arc of a circle, as indicated at 39, and this cross-member may assist in holding the pail in its tilted position. A wedging member 41 is provided on the inside of the member 29 and this member is slotted as indicated at 42. The wedging member 41 is held in place against the member 29 by means of a bolt 43 and thumb nut 44, with the bolt passing through the slot in the member 41 and a suitable opening in the member 29. The plate 41 may be adjusted back and forth to accommodate different sizes of pails. In its retracted position the largest size pails may be used in the device, while in the extended position smaller pails may be used.

In use the pail may be placed in the device either on the support 27 beneath the animal, or

may be tilted as shown in Figure 1, which is the position generally preferred. The operator is thus afforded a solid substantial stool which holds the pail in the most desirable position and also 5 protects the pail from falling or being kicked over. The bottom of the pail is always supported in such a manner that it cannot become fouled by manure or the like in the stall.

It is apparent that modifications of my invention 10 may be made by those skilled in the art and such modifications may be made without departing from the spirit and scope of my invention as set forth in the appended claims.

I claim as my invention:

- 15 1. In combination, a milking stool, a platform supported in extended position with reference to the stool, and a pair of convergent pail supporting arms secured to the platform and to the stool for forming a V-shaped opening for holding the pail.
- 20 2. In combination, a milking stool, a platform, and means for engaging the platform to the milking stool including a pair of inclined pail supporting arms which form a V-shaped opening adapted for supporting the pail.
- 25 3. A milking stool including a seat, a seat support, a platform, means for securing the platform

to the seat support, and pail engaging means including convergent members associated with the platform and seat adapted to form a V-shaped opening for holding a pail in tilted position.

4. A milking stool including a seat, a seat support, a platform, means for securing the platform to the seat support, pail engaging means consisting of convergent members associated with the platform and seat for holding a pail in tilted position, and an additional pail engaging means 10 carried by one of the convergent members, the said additional means being adapted for movement to permit securing of different size pails.

5. In combination, a milking stool and pail support comprising a pair of stool supporting 15 upright members, a pair of braces engaging the supporting members, a seat secured on top of the braces and supporting members, a pair of pail supporting frame members extending horizontally from the stool supporting members, and a 20 pair of inclined converging pail supporting arms extending from the free ends of the pail supporting frame members to the stool supporting members, the last named members converging to afford means for holding a pail in tilted position. 25

PARK LESTER NEWBOLD.
